F. KLEE, OF BROOKLYN, E. D., NEW YORK.

Letters Patent No. 86,082, dated January 19, 1869.

IMPROVED FASTENING FOR COVERS OR STOPPERS OF BOTTLES, JARS, &c.

The Schedule referred to in these Letters Patent and making part of the same.

To all whom it may concern:

Be it known that I, F. KLEE, of Brooklyn, E. D., in the county of Kings, State of New York, have invented a new and useful Improvement in Fastening Screw-Thimbles to the Necks of Bottles, Jars, &c.; and I do hereby declare the following to be a full, clear, and exact description thereof, which will enable those skilled in the art to make and use the same, reference being had to the accompanying drawing, forming part of this specification, in which drawing—

Figure 1 represents a vertical central section of this invention.

Figure 2 is a detached section of the connecting-tube.

Similar letters indicate corresponding parts.

This invention consists in the arrangement of a sheet-metal connecting-tube, which is provided with lugs, and with a screw-thread at its outer end, in combination with the screw-thimble and with the neck of a bottle, jar, or other vessel, which is grooved to receive the lugs of the connecting-tube, and which is also provided with a shoulder, in such a manner that when the connecting-tube is introduced into the neck of the vessel, its inner edge can be bent out under the shoulder of said neck, and by screwing the thimble on the screw-thread, at the outer end of the connecting-tube, a firm and durable connection is effected between said thimble and the neck of the vessel, the joint being rendered tight by a packing-ring of cork, or other material, and by these means the objectionable use of cement can be dispensed with.

A represents a vessel, of glass, china, stone-ware, or other material of a similar nature, and provided with a neck, B, to which the screw-thimble C is to be connected.

The connection is effected by a tube, D, which is made of brass, or other soft and pliable sheet-metal, and provided with lugs a, and with a screw-thread, b, as clearly shown in fig. 2 of the drawing.

The neck of the vessel A is furnished with grooves c, to receive the lugs a, and with a shoulder, d, as shown in fig. 1, so that when the tube D has been introduced, its inner edge can be turned out under said shoulder, as shown.

To facilitate the operation of turning out its edge,

said tube may be provided with a series of incisions in its inner edge, but if the metal from which said tube is made, is soft and thin, these incisions can be dispensed with.

After the tube D has been secured in the neck of the vessel, the screw-thimble C is attached to it by means of an internal screw-thread, e, which screws on the thread b of the connecting-tube, and in order to make the joint tight, a ring, f, of cork or other suitable material is interposed between the top edge of the neck B and the thimble C.

The connection between the tube D and thimble C may be made permanent by solder, or by pressing the top edge of the tube out into a groove turned, for that purpose, into the inner edge of the thimble.

By these means, a firm, durable, and air-tight connection is effected between the thimble C and the neck of the vessel, without the necessity of using cement of any kind, and my mode of fastening the screw-thimbles is particularly valuable for vessels intended to receive petroleum, or other liquid of such a nature, that it is difficult to find a cement capable of resisting its action.

I am aware that bungs for barrels have been constructed, in which a connecting-tube of cast-metal is secured in place by a nut on the outside of the barrel, instead of the screw-thimble which I use, the cap in these bungs being screwed directly on the connecting-tube, instead of on the nut or on the screw-thimble which I use; but by screwing the cap on the thimble, I am enabled to make the connecting tube of thin metal, which can be more readily inserted within the jar or vessel, and clinched on the inside.

Having thus described my invention, What I claim as new, and desire to secure by Letters Patent, is—

The sheet-metal connecting-tube D, provided with lugs a, in combination with the screw-thimble C, and with the neck B, substantially as and for the purpose described.

F. KLEE.
